GEOEGE W. CRAVENS, OF CHICAGO, ILLINOIS, ASSIGNOR TO DELTA-STAR ELECTRIC COMPANY, OF CHICAGO, ILLINOIS, A CORPORATION OF ILLINOIS.

ELECTRIC SWITCH.

1,092,245.

Specification of Letters Patent.

Patented Apr. 7, 1914.

Original application filed July 30, 1910, Serial No. 574,598. Divided and this application filed November 27, 1911. Serial No. 662,575.

To all whom it may concern:

Be it known that I, GEORGE W. CRAVENS, a citizen of the United States, residing at Chicago, county of Cook, State of Illinois, have invented a certain new and useful Improvement in Electric Switches, and declare the following to be a full, clear, and exact description of the same, such as will enable others skilled in the art to which it pertains to make and use the same, reference being had to the accompanying drawings, which form a part of this specification.

There are two common forms of small electric switches, such as wall switches, namely those which are operated by push buttons and those provided with rotatable handles or finger pieces.

My invention relates particularly to the former type and has for its object to improve the same.

In the ordinary push button switch the operating pressure or force must be applied in a predetermined direction, namely that in which the push button reciprocates. If the pressure be at an angle to the line of movement of the push button, there is a component of force which tends to bind the push button and, as the angle increases this component increases so that when the force is applied at a comparatively small angle to the direction in which the push button may move, the push button will fail to operate.

Specifically considered, the object of my invention is to provide a substitute for the push button which shall be so arranged that the switch may be operated by a force or pressure which is not limited as to direction as in the case of the push button, but may be applied at any angle which will give a component in a predetermined direction.

This application is a division of my prior application Serial No. 574,598 filed July 30, 1910, and I shall therefore illustrate and describe the switch as applied to the particular use claimed in the foregoing application; it being of course understood that my switch may be used wherever the two forms of switches to which I have heretofore referred could be applied.

The various features of novelty whereby my invention is characterized will herein-after be described in the claims; but, for a full understanding of my invention and of

its object and advantages, reference may be had to the following detailed description taken in connection with the accompanying drawing, wherein:

Figure 1 is a sectional view through the switch illustrating it as applied to the upper berth of the sleeping car, the switch being shown closed; Fig. 2 is a view similar to Fig. 1 showing the switch open; and Fig. 3 is a front view of the switch.

Referring to the drawing, F represents the switch box or casing containing a switch of any suitable type. The particular use of my switch which I have illustrated makes it preferable that the switch be one which automatically closes when free to do so and is opened by the application of pressure. It will of course be understood, however, that this action may be reversed. In the arrangement shown, there is an ordinary knife switch comprising an arm G which is pivotally mounted between its ends at g and is adapted to engage with contact pieces H in its closed position.

I is a spring which tends normally to hold the arm in engagement with the co-operating contact pieces. For moving the switch arm against the tension of the spring I have provided a swinging plate or shoe L which is of considerable area and is adapted, in one position, to lie substantially flush with the front face f of the switch case or box. The member L is pivotally mounted on the case or box by means of journals l arranged at one end thereof and lying parallel with the front face of the case or box. The motion of the member L may be translated into a motion of the switch arm by any suitable means, preferably by means of a strut K interposed between the free end of the member L and one end of the switch arm.

The member K may be a simple strut because the opening pressure on the switch is in the form of a thrust. Where the switch is mounted with the pivotal axis of the member L horizontal as illustrated, the member L will naturally hang in the proper relation to the strut; but when the switch is disposed in any other position there might be a tendency for the member L to swing out of its operative position unless it were positively connected to the switch arm. In the preferred arrangement, therefore, the member

K is preferably pivotally connected at its ends to the switch arm and to the operating member, respectively.

It will be seen that a force applied to the outer face of the swinging shoe or plate in any direction from one perpendicular to the front face of the switch box or casing to one parallel of this face, (as long as the latter force is directed from the pivoted end of the member L toward the free end), will cause the shoe or plate to swing inwardly and operate the switch. Furthermore the large area of the shoe or plate makes it unnecessary that the force be directed to one particular spot as in the case of a push button, considerable latitude being therefore allowed as to the point at which the pressure may be applied. This latter feature is an important one no matter where the switch is employed: if it be employed as a wall switch and is to be operated by pressure of the thumb or fingers, it is more easily operated in the dark than the ordinary push button; if the switch is located in a position which does not allow ready access, then again its operation is more convenient than where a push button is employed; and finally, where the switch is to be operated by some movable member mounted adjacent thereto, the same delicate adjustment is not required as in the case of a push button and the operating mechanism is not so apt to become out of repair.

In the preferred form the plate L is hinged at one end at a point within the switch box and adjacent to the front face thereto so as to be capable of swinging through an opening f' in said face; and it is provided with rearwardly extending flanges l' along the edges at right angles to the axis of the hinge in order to keep the opening covered when the plate swings out as indicated in Fig. 1.

In the arrangement illustrated, the switch is shown as mounted in the wall A of a sleeping car or other structure and is adapted to be operated by a movable member B pivotally mounted on this wall; the member B being provided with a cam M for engaging with the shoe or plate L. It will be seen that the cam has a sliding action on the shoe so that a considerable portion of the angular movement of the member B is available for actuating the switch, no delicate adjustment of the parts being required since it will always be possible to obtain sufficient movement by an adjustment which is only reasonably close. The cam may be made yielding or resilient, thus further reducing the need for accurate adjustment. 60

While I have illustrated and described only a single preferred form of my invention, I do not desire to be limited to the particular structural details thus illustrated and described; but intend to cover all forms and arrangements which fall within the terms employed in the definitions of my invention constituting the appended claim.

I claim:

In combination, a switch box, a switch within the box, said box having a large opening in one side, a plate hinged at one end in said opening and forming a closure therefor, means between the opposite end of the plate and the switch for transmitting motion from the plate to the switch, and an operating member for said plate pivotally supported adjacent thereto and having a part adapted to make sliding contact with the face of said plate. 75

In testimony whereof, I sign this specification in the presence of two witnesses.

GEORGE W. CRAVENS.
